Application February 1, 1947, Serial No. 725,940

8 Claims. (Cl. 15—133)

1.

The present invention relates in general to dispensing devices and, more particularly, to devices of this type having a fountain or reservoir for supplying a dispensable medium to an applicator associated with the dispenser, the invention pertaining particularly to a cosmetic device for applying a liquid medium to fingernails, lips and the like.

An object of the invention is to provide an improved fountain-type dispensing device which is of pleasing appearance, which is convenient to use and from which a liquid medium may be dispensed in closely controlled amounts.

A further object of the invention is to provide an improved fountain-type dispensing device having a replaceable brush-type applicator for applying the liquid medium within the reservoir of the device to a given surface, the brush being supplied with the liquid medium by retracting the brush into the reservoir of the device and thereafter advancing the brush from the reservoir into working position.

A still further object of the invention is to provide a fountain-type dispensing device wherein the fluid medium within the reservoir is prevented from leaking or evaporating both while the device is closed and while it is in use.

A still further object of the invention is to provide a fountain-type dispensing device having a brush-type applicator and an applicator-manipulating means which is adapted to be rendered inoperative whenever the cap of the device is in place, so as to preclude any damage to the applicator-brush; and to be made operative automatically whenever the cap is removed so as to enable the applicator-brush to be moved into position for use.

A still further object of the invention is to provide a superior cosmetic device for applying a liquid medium to fingernails, lips and the like, the device being one which may be conveniently carried in a pocketbook and which is provided with an applicator-brush maintained normally within the liquid reservoir of the device and adapted to be projected from the reservoir into operating position by movement of the latter relative to the applicator.

A still further object of the invention is to provide a superior cosmetic device wherein an applicator-brush is embraced by a guard within the fluid-reservoir of the device, the guard having the dual function of maintaining the shape of the brush and of partially closing the open end of the reservoir so as to prevent the fluid medium from evaporating therefrom while the device is in use.

2.

With the above and other objects in view, as will appear to those skilled in the art from the present disclosure, this invention includes all features in the said disclosure which are novel over the prior art.

In the accompanying drawings, in which certain modes of carrying out the present invention are shown for illustrative purposes:

Fig. 1 is a plan view of the improved cosmetic applicator of this invention, the elements of the applicator being in their normal relationship in which the applicator is adapted to be carried in a pocketbook or the like;

Fig. 2 is an enlarged sectional elevation on line 2—2 of Fig. 1, the several elements of the cosmetic applicator being in the same relationship as shown in Fig. 1;

Fig. 3 is a sectional end elevation of the applicator on line 3—3 of Fig. 2 showing details of the brush-guard;

Fig. 4 is a sectional end elevation on line 4—4 of Fig. 2 showing details of the barrel-reservoir and sleeve;

Fig. 5 is an enlarged sectional elevation of the applicator similar to Fig. 2 except that the cap of the applicator has been removed from the front end thereof and placed on the rear end thereof, as a consequence of which the applicator has moved forwardly in the barrel-reservoir;

Fig. 6 is an enlarged sectional elevation similar to Fig. 5, but after the sleeve has been advanced along the barrel by the brush-manipulator to project the brush beyond the front end of the barrel;

Fig. 7 is an enlarged sectional elevation similar to Fig. 5 but with the brush-manipulator retracted to the position it assumes when the brush and barrel-reservoir are to be filled with liquid;

Fig. 8 is a plan view of the applicator partly in section with the cap removed, the position of the barrel-reservoir with respect to the brush-manipulator being such as to show the index on the barrel, thereby indicating that the cap may be threadedly engaged with the screw threads on the outer end of the applicator;

Fig. 9 is a plan view of the applicator, partly in section, with the cap screwed onto the front end thereof, as a consequence of which the barrel-reservoir has been disengaged from the brush-manipulator;

Fig. 10 is a plan view similar to Fig. 9 but with the brush-manipulating means retracted rearwardly on the barrel so as to determine by the index on the barrel whether or not the cap is closed tightly on the end of the barrel; and

Fig. 11 is a perspective view of the brush-guard.

For the purpose of illustrating the present invention, the description below relates to a fountain-type dispensing device which is adapted to dispense a cosmetic such as, for example, a nail polish or lacquer, but it will be understood that the present embodiment of the invention is by way of illustration only and that the device may be used for dispensing other liquid or semi-liquid mediums as, for example, mucilage, paint and the like. Referring to the drawings, the cosmetic-dispensing device embodies a barrel indicated generally at 15 and comprising a cylindrical tubular-member consisting preferably of metal, although a suitable plastic material may be used, and having a plurality of external screw threads 16 at its forward end, the threads being terminated rearwardly on the forward end of the barrel by an annular relief-recess 17. The forward end of the barrel 15 has an end-closure or end wall 18 provided with an axial aperture 19 communicating with the front and rear faces 20 and 21 respectively of the end wall 18, the sides of the aperture 19 converging slightly from the outer face 20 to the inner face 21 of the end wall 18. The outer face 20 of the barrel is shown as a shallow countersink, but may be a planar surface at substantially right angles to the longitudinal axis of the barrel, whereas the inner face 21 of the end wall 18 constitutes a relatively-deep frusto-conical countersink, the forward end of which intersects the rear end of the aperture 19, and the rear edge of which intersects the forward end of the substantially-cylindrical bore 22 of the barrel. The diameter of the internal bore 22 of the barrel is substantially uniform from its forward end rearwardly to a point substantially one-third the overall length of the bore 22, as indicated by the annular shoulder 22a, the diameter of the bore rearwardly of the shoulder 22a being slightly larger, for the purpose hereinafter described. The rear end of the barrel 15 is provided with an external helical screw thread 23 having a relatively-steep pitch, the threads being coarse and substantially rectangular in cross section. The rear end of the barrel is adapted to be closed by an apertured disk-shaped plug 24 which in the present embodiment seats against the shoulder 25 of a counterbore 26, the plug 24 being held securely on its seat by an annular flange 27 spun over the outer edge of the rear face of the plug 24. The latter is a preferred construction but it will be understood that any other equivalent means may be used for securing the plug 24 in the counterbore 26 at the rear end of the barrel. The aperture 28 of the plug 24 is adapted to support a bushing 29 having a cylindrical bore of uniform diameter and comprising an external shank-portion 30 and a stem-portion 31 of reduced diameter, the latter being adapted to fit tightly in the aperture 28 of the plug 24. The rear end of the stem-portion 31 of the bushing is shown peened over the annular rim of the plug-aperture 28 and is adapted thereby to effectively hold the front face of the plug 24 tightly against the annular shoulder 32 at the lower end of the shank-portion 30 of the bushing. In accordance with the aforesaid construction, all joints between the plug 24, the barrel-counterbore 26 and the bushing 29 are effectively sealed so as to preclude any leakage therebetween, the plug and bushing-assembly consti-

tuting an apertured end-closure or bottom for the rear end of the barrel.

Mounted on and arranged to slide freely along the barrel 15 is a cylindrical sleeve 33, the forward end of which is provided with a relatively-short substantially-longitudinal indenture constituting a spline 34 adapted to engage in a longitudinal groove 35 formed in the outer surface of the barrel (see Figs. 1, 3 and 4), to prevent rotation of the sleeve relative to the barrel, the longitudinal barrel-groove 35 extending uninterruptedly from the rear end of the barrel forwardly to the relief-recess 17. The rear end of the sleeve 33 is upset to provide a cylindrical cuff-portion 36 of substantially uniform diameter and having relatively-thin walls, the internal diameter of the cuff being substantially equal to the outside diameter of the sleeve. In the present embodiment, the cuff is formed as an integral extension of the rear end of the sleeve and in a manner such that the rear end of the sleeve forms an annular internal shoulder 37 at the forward end of the cuff.

The cuff-portion 36 of the sleeve is adapted to rotatably support the forward end of a substantially-cylindrical applicator-manipulating means indicated generally at 38. The latter comprises a cylindrical thimble or finger-piece 39 of relatively-thin wall section, the forward end of which is characterized by a rim-portion 40 of relatively-thick cross section hereinafter referred to as a "retaining-band," the thickness of the latter corresponding substantially to the thickness of the body-portion of the sleeve. The outside diameter of the retaining-band 40 is substantially equal to the inside diameter of the cuff 36 of the sleeve whereby the retaining-band portion of the finger-piece is adapted to be assembled in the cuff and to have a close rotatable fit therein, the forward end of the finger-piece being in abutting relationship with the shoulder 37 of the sleeve. The finger-piece 39 is adapted to be retained in its assembled position in the cuff by spinning over the rear end of the latter beneath the annular shoulder 41 of the retaining-band 40. The applicator-manipulating means 38 is thus held from moving longitudinally with respect to the sleeve 33 but is enabled to rotate freely in the cuff-portion 36 thereof. The rear end of the finger-piece 39 is provided with a substantially-solid head 42, the outside diameter of which corresponds substantially to the outside diameter of the barrel 15, for the purpose hereinafter described, the head being provided with a finger-grip comprising an annular flange 43 which is hexagonal in shape so as to provide a plurality of flat surfaces 44 adapted to prevent the device from rolling when placed on a flat surface or the like. The forward end of the finger-piece 38 is provided with an internal screw thread 45 corresponding in size and pitch to the screw thread at the rear end of the barrel, the screw thread 45 being adapted to engage the screw thread 23 at the rear end of the barrel to advance and retract the sleeve relative to the barrel, as hereinafter described.

The head 42 is provided preferably with a substantially-flat end 46 for temporarily supporting the device in an upright position on a table-top, chair-arm or the like, and has an axial aperture 47 adapted to receive and support a rod 48, the rear end of which is secured in the aperture 47 of the head 42 by fastening-means comprising a pilot-screw 49 and lock-screw 50, both of which

are threadedly engaged in a radial aperture in the head 42, the pilot-screw 49 having a stem 51 arranged to engage in an axially-aligned radial aperture 52 in the rear end of the rod 48. The rod 48 extends forwardly from the head 42 through the bushing 29 of the barrel-bottom plug 24, the shank of the rod being adapted to make a close substantially-leakproof fit in the bore of the bushing 29, although permitting the bushing to slide longitudinally on the rod 48. The rear end or bottom of the barrel is thus supported and guided by the rod 48 for longitudinal movement in the rear end of the sleeve 33 and in the forward end or finger-piece 39 of the applicator-manipulating means 38, the internal diameters of the sleeve and finger-piece being equal, so as to provide a continuous bore of uniform diameter. It will be clear that the rear end of the barrel is effectively closed by the plug, bushing and rod-assembly, as a consequence of which the internal bore 22 of the barrel constitutes a cavity closed at one end and capable of retaining a liquid medium. The barrel-bore 22 is, therefore, herein-after referred to as the "barrel-reservoir" or "reservoir".

Secured to or formed integrally on the forward end of the rod 48 is an enlarged substantially frusto-conically-shaped-head 53 which constitutes a valve-head for closing off the aperture 19 in the forward end of the barrel, as hereinabove described. A longitudinal aperture 54 is drilled or otherwise formed axially in the forward end of the rod 48 and its valve-head 53 to accommodate the ferrule 55 of an applicator which, in the present embodiment, comprises a brush 56. It will be understood, however, that applicators of various forms may be used. The ferrule 55 of the brush 56 is preferably wood, although it may comprise other suitable materials, and is adapted to make a snug fit in the axial aperture 54 in the end of the rod 48, so as to retain the brush therein during the normal use of the device, the ferrule being capable of removal, however, for the replacement of a worn-out brush. Mounted on the rod 48, between the forward end of the barrel-bushing 29 and the underside or base of the fixed valve-head 53, is a collar 57, the said collar being adapted to slide substantially freely along the rod 48 and to constitute supporting means for a brush-embracing guard, indicated generally at 58 and shown clearly in Fig. 11. To this end, the collar 57 is provided with an annular flange 59 circumscribing its base, the shoulder of the flange constituting a seat for the base 60 of the brush-guard 58, the base of which comprises a ring having an axial aperture 61 dimensioned to make a snug fit on the collar; and a counterbore 62 on its underside to accommodate the annular flange 59 of the collar. The lower edge 63 of the guard-base is spun over the bottom of the collar 57 to lock the collar and guard in assembled relationship. The base of the brush-guard is provided with three shoes 64 formed integrally therewith and projecting radially therefrom in substantially-equal angular relationship, the outer end of each shoe comprising a substantially-cylindrical surface of revolution adapted to slidingly engage the restricted bore-portion of the barrel forwardly of the internal shoulder 22a. The shoes 64 thus constitute guides for supporting the rod 48 and the brush and brush-guard assembly in the forward end of the barrel-reservoir, substantially in axial alignment with the aperture 19 in the end wall of the barrel, as clearly indicated in Figs. 5 and 6. However, when the rod, brush and

brush-guard assembly are retracted rearwardly in the barrel below the internal shoulder 22a thereof, as indicated in Fig. 7 and as hereinabove described, the shoes of the brush-guard no longer make uniform sliding engagement with the internal walls of the barrel. The latter provision is a preferred construction in order to reduce to a minimum frictional engagement of the shoes 64 with the interior wall of the barrel, for it has been found that the wear which occurs between these surfaces may form a film or coating of metal oxides or other foreign material which has been known to discolor the liquid medium within the reservoir of the barrel.

Extending upwardly substantially vertically from each of the three shoes 64 of the guard, is a post 65. The upper ends of the three posts are joined integrally with or otherwise secured to the outer edge of the guard-head 66 which comprises a dished frusto-conically-shaped member having a central aperture 67 to accommodate the applicator-brush 56. The diameter of the aperture 67 is such that its annular rim 68 is adapted normally to closely embrace the bristles of the brush, as shown clearly in Figs. 2, 5 and 7, to retain the bristles in their predetermined and preferred shape. The slope of the outer frusto-conical surface of the guard-head 66 corresponds substantially to the slope of the countersink 21 in the end wall 18 of the barrel, so that when the brush-guard is moved forwardly relative to the barrel, the head 66 of the guard will seat tightly in the countersink 21, as shown in Fig. 6. In this position of the applicator-guard, its head 66 extends part way into the aperture 19 so as to reduce its effective size to the actual size of the aperture 67 in the head of the brush-guard. In accordance with this construction, the guard-head may be said to partially close the aperture 19 in the end of the barrel and thus to effectively reduce evaporation and leakage of liquid from the reservoir. The underside of the frusto-conical guard-head 66 is also a frusto-conical surface, the slope of which corresponds substantially to the slope of the valve-head 53 of the rod 48 and is herein-after referred to as the "valve-seat 68 of the valve-head".

Mounted on the brush-supporting rod 48 and engaged at its opposite ends against the rear face 50 of the guard-supporting collar 57 and the bottom of the barrel-reservoir 22 respectively, is a coil-spring 69 which, in conjunction with a cover, is adapted to control the relative displacement of the barrel, sleeve and brush-manipulating assembly, as hereinabove described.

The cover or cap of the device is indicated generally at 70 and comprises a substantially-cylindrical tubular member closed at its forward end by a suitable plug 71 which may be a separate member firmly secured therein in any suitable manner, or an integral end-closure of the tubular member. The plug 71 is provided with a concentric rearwardly-extending protuberance or stopper 72 of reduced diameter, the peripheral walls of which are tapered to correspond to the internal taper of the aperture 19 in the end wall 18 of the barrel, so that the stopper 72 may make a fluid-tight fit therein. To this end, the interior wall of the cap-member adjacent the stopper 72, is provided with internal threads 73 adapted to threadedly engage the external threads 74 in the end wall 18 of the barrel, so that by screwing the cap-member 70 onto the forward end of the barrel, the stopper 72 may be forced into the aperture 19 in the end wall 18 of the barrel. In this

connection, it should be pointed out that the distance from the rear end 74 of the cap 70 to the rearmost thread 73 in the forward end thereof is critical and must be maintained with great precision, for the purpose hereinafter described. Moreover, since the internal diameter of the cap corresponds substantially to the outside diameter of the barrel, the cap is adapted to be slipped over the rear end 42 of the finger-piece 39 (which is of corresponding diameter) when the device is in use, as indicated in Fig. 6.

At this point, it may be pointed out that the several elements constituting the applicator of this invention are adapted to take several different positions relative to each other in carrying out the several functions of the device. Figs. 1 and 2 of the drawings illustrate the device when it is capped and tightly sealed for transportation, the elements being in the relationship shown in Fig. 2, which is hereinafter referred to as the "carrying position" of the device. Fig. 5 shows the related positions of the elements after the cap has been removed from the forward end of the barrel, the device being hereinafter referred to as being in its "normal position." Fig. 6 shows the related positions of the elements of the device when the brush has been advanced for use, the device being hereinafter referred to as being in its "operating position"; and Fig. 7 shows the related elements of the device in the position for introducing a liquid into the reservoir and for filling the brush, which position is hereinafter referred to as the "charging position" of the device.

The operation of the device may be described briefly as follows:

Assuming that the cap 70 has been threaded onto the forward end of the barrel, as shown in Figs. 1 and 2, so as to seat its stopper 72 in the aperture 19 in the end wall of the barrel, in so doing, the rear end 74 of the cap 70 will have engaged the forward end of the sleeve 33 and displaced the latter longitudinally rearwardly on the barrel 15 to the position shown in Fig. 2 corresponding to its "carrying position" and in so doing will have retracted the applicator-manipulating means 38, together with the rod 48, brush 56 and brush-guard 58, into the body of the reservoir 22 against the force of the compressed spring 69, in which position the brush and brush-guard are withdrawn out of the aperture 19 in the end of the barrel, the latter being completely sealed by the stopper 72. With the elements of the applicator in this assembled relationship, the applicator is adapted to be carried successfully in a lady's pocketbook, handbag or the like, without fear of leakage.

It will be appreciated, however, that before it is possible to displace the sleeve and its attached brush-manipulating means longitudinally rearwardly relative to the barrel, the threads 45 of the finger-piece 39 must have been disengaged previously from the threads 23 of the barrel by rotating the finger-piece 39 relative to the barrel, in a counterclockwise direction, which is the direction of rotation of the finger-piece for retracting the brush into the reservoir of the barrel.

On displacing the brush-manipulating means rearwardly longitudinally relative to the barrel, the threads of the finger-piece 39 will be carried out of engagement with the threads of the barrel 15, as a consequence of which the brush-manipulating means is temporarily disabled so that in the event its finger-piece 39 should be rotated while the cap 70 is in place, the brush would not be moved forwardly against its stop-

per 72, thereby precluding damage from this cause, the brush, brush-guard and brush-manipulating means all being positively held in a retracted position in the reservoir by engagement 5 of the rear end 74 of the cover with the forward end of the sleeve.

Now if the cap 70 is unscrewed, the gradual forward movement of the cap relative to the barrel permits the spring-loaded brush, brush-manipulating means and sleeve to move forwardly until the leading thread of the cap engages the rearmost thread of the barrel, at which time the head 66 of the brush-guard will engage or be in close proximity to the countersink 21 in the end wall 18 of the barrel, at which time the cap has been disengaged and withdrawn from the forward end of the barrel. The elements of the applicator are now in their normal position, as shown in Fig. 5, in which position the threads of the finger-piece 39 are in a position to engage the threads of the barrel 15 so that by rotating the finger-piece 39 in a clockwise direction, the brush, brush-supporting rod and valve-head will be moved forwardly longitudinally into operating position, as shown in Fig. 6. As pointed out above, when the cap 70 is off and the elements are in their normal position of Fig. 5, proximity of the guard-head 66 to the end wall 18 reduces the effective size of its aperture 19. Moreover, with the brush in its retracted position with respect to the guard, the brush is embraced by and substantially fills the aperture 67 in the head of the guard, as a consequence of which evaporation of liquid from the reservoir 35 22 is appreciably reduced. It will be understood, however, that if the device were inverted, liquid within the reservoir would seep through the bristles of the brush and form drops at the end thereof. However, when the device is ready for use, as shown in Fig. 6, the brush 56 will have been advanced out of the aperture 67 of the brush-guard by rotating the finger-piece 39 in a clockwise direction, and the guard-head 66 and valve-head 53 of the rod 48 will have been brought into tight engagement with the counterbore 21 of the end wall 18 and the valve-seat 68 of the applicator-guard respectively, so as to effectively close off the open end of the reservoir. Consequently, when inverted and in use, liquid is 40 positively prevented from escaping from the aperture 19 in the forward end of the reservoir. Assuming now that the device has been used until the liquid contained in the brush has been exhausted, then to bleed more liquid to the brush, 45 it is only necessary to rotate the finger-piece 39 in a counterclockwise direction sufficiently to unseat the valve-head 53 of the brush-supporting rod from the valve-seat 68 of the brush-guard, to permit a small quantity of liquid to flow from the reservoir 22 out of the aperture 67 of the guard-head and onto the brush, the amount of liquid which flows to the brush being regulated by controlling the size of the opening allowed between the valve-head and its valve-seat. Upon 50 obtaining a sufficient amount of liquid in the brush, the finger-piece 39 may be rotated again in a clockwise direction to close the valve against its seat to prevent additional liquid from flowing to the brush.

55 In some instances it may be desirable to charge the brush with a large amount of liquid. In this event, the finger-piece 39 is rotated in a counterclockwise direction sufficiently to retract the brush into the brush-guard and to disengage the threads of the finger-piece from the threads of

the barrel, after which the finger-piece, including the rod, brush, brush-guard and sleeve, may be drawn rearwardly longitudinally on the barrel so as to immerse the brush and brush-guard assembly in the liquid of the reservoir, as shown in Fig. 7. Thereafter, the finger-piece may be moved forwardly longitudinally relative to the barrel to re-engage its threads with the threads of the barrel and subsequently rotated clockwise to advance the brush out of the forward end of the barrel. The speed at which the brush is advanced out of the aperture of the guard will determine to some degree the amount of liquid which will be retained in the brush. Thus, if the brush is advanced rapidly, then a large amount of liquid will be retained within the brush, whereas, if the brush is advanced slowly, a large proportion of the liquid will drain off of the brush back into the reservoir. Varying the speed at which the brush is advanced from the reservoir has, therefore, substantially the same effect as wiping the brush to remove excess material therefrom.

As an additional feature of the invention, it will be noted that when the device is in its operating position as shown in Fig. 6, the guard-head 66 and valve-head 53 effectively close the rear end of the aperture 19 in the forward end of the barrel so that the former constitutes, in effect, a shallow cup-shaped pocket or reservoir at the base of the brush. In the event a large amount of liquid is contained in the brush by the charging action described above, then this excess material may drain back into the overflow reservoir at the base of the brush and supply the brush with the liquid as it is needed.

Referring to Figs. 8, 9 and 10, the invention also embodies a safety feature adapted to minimize the likelihood of improperly assembling the cap on the barrel in such a way as to allow the liquid therein to leak out. To this end, the barrel is provided with an index-mark constituting a shallow recessed groove 75 which may be colored with a suitable paint or lacquer, the forward edge 76 of the index-mark being located on the barrel at a distance from the threads at the base thereof such that when the trailing edge 78 of the rearmost thread 23 of the barrel rides on the leading edge 79 of the foremost thread 45 of the brush-manipulating means, as indicated in Fig. 8, the sleeve will have been displaced rearwardly on the barrel a distance corresponding substantially to the distance between the rear end 14 of the cap and the rearmost thread in the forward end thereof. In this position of the brush-manipulating means 38, the forward edge 76 of the index-mark will show as a narrow colored line which indicates that the threads of the cap may catch the threads at the forward end of the barrel, so that the cap may be successfully screwed thereon, in the manner pointed out above. In the event, however, that the brush-manipulating means were not rotated counterclockwise sufficiently to uncover the forward edge 76 of the index-mark, the distance from the forward edge of the sleeve to the threads at the forward end of the barrel would be less than the distance between the rearmost thread of the cap and its rear edge 14, as a consequence of which the cap could not be threaded onto the barrel. Hence, the relatively-narrow color-band which will be revealed when the brush-manipulating means has been displaced rearwardly sufficiently to permit the cap to be threaded onto the barrel, serves to indicate the proper relationship of the barrel, cap and

sleeve for securing the cap to the barrel in leak-proof relationship. Fig. 9 shows the cap assembled on the barrel. The action of threading the cap onto the barrel, as described above, moves the sleeve rearwardly on the barrel so that there is no longer any opportunity for the threads of the brush-manipulating means to engage the threads of the barrel. Moreover, when the cap is fully threaded on the barrel so as to seal the aperture 19 therein by its stopper 72, the rear end 14 of the cap will be substantially opposite the rear edge 77 of the index-mark of the barrel, being sufficiently short thereof, as indicated in Fig. 10, to leave a narrow colored band. This narrow band serves to indicate that the cover is properly secured to the end of the barrel and that the reservoir is sealed by the stopper of the cover. On the other hand, a relatively-wide index-mark or band would indicate that the cover was not screwed fully onto the barrel.

Although the device described is designed preferably for applying nail polish or lacquer for fingernails and to this end embodies a reservoir capable of holding an amount of liquid substantially equivalent to the standard-size cosmetic bottle, it will be understood that the size of the applicator may vary depending upon the specific use to which it is to be put, and that other liquid mediums may be employed such as, for example, a liquid rouge, lipstick, or mucilage, paints and the like.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

We claim:

1. In a device of the class described, in combination: a barrel having a reservoir and an apertured end wall communicating therewith; a sleeve to support said barrel, said sleeve having a telescoping connection therewith for longitudinal movement with respect thereto; an applicator; means connected to said applicator to support said applicator in said reservoir; an applicator-embracing guard slidably mounted on said applicator-supporting means within said reservoir; resilient-means arranged to urge said guard forwardly in said reservoir into engagement with the apertured end wall of said barrel to partially close the latter and in cooperation with the embraced applicator to minimize evaporation of a liquid from said reservoir; and an applicator-manipulating means secured to said applicator-supporting means said manipulating means being rotatably connected to said sleeve and provided with an internal screw-thread arranged to be engaged with an external screw-thread on said barrel so as to be effective upon rotation in one direction to move said applicator through said reservoir and said guard out of the aperture in the end wall of said barrel, and upon rotation in the opposite direction to retract said applicator into said reservoir and the embracement of said guard.

2. In a device of the class described, in combination: a barrel having a reservoir and an apertured end wall communicating therewith; a sleeve to support said barrel, said sleeve having a telescoping connection therewith for longitudinal movement with respect thereto; an applicator; means connected to said applicator to support

said applicator in said reservoir; an applicator-embracing guard slidably mounted on said applicator-supporting means within said reservoir; resilient-means arranged to urge said guard forwardly in said reservoir into engagement with the apertured end wall of said barrel to partially close the latter and in cooperation with the embraced applicator to minimize evaporation of a liquid from said reservoir; and an applicator-manipulating means secured to said applicator-supporting means, said manipulating-means being rotatably connected to said sleeve and provided with an internal screw-thread arranged to be engaged with an external screw-thread on said barrel so as to be effective upon rotation in one direction to move said applicator through said reservoir and said guard out of the aperture in the end wall of said barrel, and upon rotation in the opposite direction sequentially to retract said applicator into said reservoir and the embracement of said guard, and thereafter to disengage said guard from the apertured end wall of said barrel.

3. In a device of the class described, in combination: a barrel having a reservoir and an apertured end wall communicating therewith; a sleeve to support said barrel, said sleeve having a telescoping connection therewith for longitudinal movement with respect thereto; an applicator; means connected to said applicator to support said applicator in said reservoir; valve-means carried by said applicator-supporting means; an applicator-embracing guard slidably mounted on said applicator-supporting means within said reservoir, said applicator-embracing guard having a valve-seat; resilient-means arranged to urge the said guard forwardly in said reservoir into engagement with the apertured end wall of said barrel to partially close the latter and in cooperation with the embraced applicator to minimize evaporation of liquid from said reservoir; and applicator-manipulating means secured to said applicator-supporting means, said manipulating-means being rotatably connected to said sleeve and provided with an internal screw-thread arranged to be engaged with an external screw-thread on said barrel so as to be effective upon rotation in one direction sequentially to advance said applicator through said reservoir and said guard out of the aperture in the end wall of said barrel and to move said valve-means into engagement with the valve-seat of said applicator-embracing guard to seal the apertured end wall of said barrel, and upon rotation in the opposite direction sequentially to disengage said valve-means from the valve-seat of the said applicator-embracing guard and to retract said applicator into said reservoir and the embracement of said guard.

4. In a device of the class described, in combination: a barrel having a reservoir, an apertured end wall communicating therewith and external screw-threads at one end thereof; a sleeve to support said barrel, said sleeve having a telescoping connection therewith for longitudinal movement with respect thereto; an applicator supported in the reservoir of said barrel; applicator-manipulating means comprising a finger-piece connected to said applicator, said finger-piece being rotatably connected to said sleeve and adapted to have screw-threaded engagement with the external threads of said barrel so as to be effective upon rotation in one direction to advance said applicator through said reservoir out of the aperture in the end wall of said barrel and upon rota-

tion in the opposite direction to retract said applicator into said reservoir; and a cap to close the aperture in the end wall of said barrel, said cap being constructed and arranged to displace said finger-piece out of position for threaded engagement with said barrel so as to preclude operation of said applicator-manipulating means.

5. In a device of the class described, in combination: a barrel having a reservoir, an apertured end wall communicating therewith and external screw-threads at one end thereof; a sleeve to support said barrel, said sleeve having a telescoping connection therewith for longitudinal movement with respect thereto; an applicator supported in the reservoir of said barrel; applicator-manipulating means comprising a finger-piece connected to said applicator, said finger-piece being rotatably connected to said sleeve and adapted to have screw-threaded engagement with the external threads of said barrel so as to be effective upon rotation in one direction to advance said applicator through said reservoir out of the aperture in the end wall of said barrel and upon rotation in the opposite direction to retract said applicator into said reservoir; and a cap to close the aperture in the end wall of said barrel, said cap being adapted to have threaded engagement with the apertured end wall of said barrel and arranged to abut the forward end of said sleeve whereby rotation of said cap in a direction to threadedly engage the apertured end wall of said barrel moves said sleeve rearwardly on said barrel and displaces said finger-piece out of position for screw-threaded engagement with said barrel, thereby precluding operation of said applicator-manipulating means.

6. In a device of the class described, in combination: a barrel having a reservoir, an apertured end wall communicating therewith and external screw threads at opposite ends thereof; a sleeve to support said barrel, said sleeve having a telescoping connection therewith for longitudinal movement with respect thereto; an applicator supported in the reservoir of said barrel; applicator-manipulating means comprising a finger-piece connected to said applicator, said finger-piece being rotatably connected to said sleeve and adapted to have screw-threaded engagement with the extreme threads at the lower end of said barrel so as to be effective upon rotation in one direction to advance said applicator through said reservoir out of the aperture in the end wall of said barrel and upon rotation in the opposite direction to retract said applicator into said reservoir; and closure-means for said device comprising a cap having a stopper, said cap being adapted to have screw-threaded engagement with the apertured upper end of said barrel and to abut the forward end of said sleeve so as to be effective upon rotation in a direction to threadedly engage the apertured end wall of said barrel to force the stopper into the aperture in the end wall of said barrel and seal the latter and simultaneously to move said sleeve rearwardly on said barrel so as to displace said finger-piece out of position for screw-threaded engagement with said barrel, thereby to preclude operation of said applicator-manipulating means.

7. In a device of the class described, in combination: a barrel having a reservoir, an apertured end wall communicating therewith and external screw threads at opposite ends thereof; a sleeve to support said barrel, said sleeve having a telescoping connection therewith; a spline interconnecting said barrel and said sleeve to per-

mit longitudinal movement only of said sleeve relative to said barrel; an applicator supported in said reservoir; applicator-manipulating means comprising a finger-piece rotatably connected to said sleeve and adapted to have threaded engagement with the external threads at the lower end of said barrel; a rod secured at its rear end to said finger-piece and extending forwardly through said reservoir, said rod having an aperture in its forward end to removably support said applicator; an applicator-embracing guard slidably mounted on the forward end of said rod; a barrel-bushing in the bottom of said reservoir and mounted on the rear end of said rod to slidably support the inner end of said barrel; and resilient-means carried on said rod arranged to engage at its forward end against said applicator-embracing guard and at its rear end against the barrel-bushing of the reservoir to urge said guard into engagement with the apertured end wall of said barrel whereby said guard is adapted to partially close the latter and in cooperation with the embraced applicator to minimize evaporation of liquid from said reservoir, said resilient means being adapted also to urge the finger-piece into position for threaded engagement with the external threads at the lower end of said barrel whereby rotation of the finger-piece in one direction effects the retraction of said barrel rearwardly relative to said sleeve to project said applicator through said guard and out of the aperture in the end wall of said barrel.

8. In a device of the class described, in combination: a barrel having a reservoir, an apertured end wall communicating therewith and external screw threads at opposite ends thereof; a sleeve to support said barrel, said sleeve having a telescoping connection therewith; a spline interconnecting said barrel and said sleeve to permit longitudinal movement only of said sleeve relative to said barrel; an applicator supported in said reservoir; applicator-manipulating means comprising a finger-piece rotatably connected to said sleeve and adapted to have threaded engagement with the external threads at the lower end of said barrel; a rod secured at its rear end to said finger-piece and extending forwardly through said reservoir, said rod having an aperture in its forward end to removably support said applicator; an applicator-guard slidably mounted on the forward end of said rod; a barrel-bushing in the bottom of said reservoir mounted on the

5 rear end of said rod to slidably support the inner end of said barrel; resilient-means carried on said rod arranged to engage at its forward end against said guard and at its rear end against the barrel-bushing of the reservoir normally to urge said guard into engagement with the apertured end wall of said barrel whereby said guard is adapted to partially close the latter so as to prevent evaporation of liquid from said reservoir, said resilient means being adapted also to urge the finger-piece into position for threaded engagement with the external threads at the lower end of said barrel whereby rotation of said finger-piece in one direction effects the retraction 10 of said barrel rearwardly relative to said sleeve to project said applicator through said guard and out of the aperture in the end wall of said barrel; and closure-means for said device comprising a cap adapted to close the aperture in the end wall of said barrel, said cap being adapted to have screw-threaded engagement with the apertured upper end of said barrel and to abut the forward end of said sleeve so as to be effective upon rotation in a direction to threadedly engage the apertured end wall of said barrel to move said sleeve rearwardly relative to said barrel and thereby to displace said applicator-manipulating finger-piece out of position for threaded engagement with said barrel.
